LLP(57) **CLAIM**

The ornamental design for a compressible container, as shown and described.

DESCRIPTION

FIG. 1 is a perspective view showing my new design for a compressible container;

FIG. 2 is a side elevational view thereof;

FIG. 3 is a top view thereof;

FIG. 4 is a bottom view thereof; and,

FIG. 5 is a side elevational view showing the compressible container in FIGS. 1-4 in a compressed state.

The broken lines are included for the purpose of illustrating a portion of the compressible container that forms no part of the claimed design.

The appearance within the unshaded central circular region of FIG. 4 forms no part of the claimed design.
